UNITED STATES PATENT OFFICE.

WILLIAM G. MOLAND, OF PHILADELPHIA, PENNSYLVANIA.

BOOTJACK.

Application filed April 23, 1926. Serial No. 104,004.

My invention relates to boot jacks, and it relates more particularly to that type of boot jack which is adapted to be collapsed into a relatively small size, and which is 5 provided with means for engaging the toe of the boot as well as the heel thereof, whereby tightly fitting riding boots of the type now commonly worn may be readily removed by the wearer.

10 The object of my invention is to provide a simple and efficient boot jack which may be readily collapsed or folded so as to occupy a relatively small space, whereby the same may be conveniently carried in the baggage 15 of the owner. A further object of my invention is to provide improved means for engaging the toe portion of the boot, as well as the heel thereof, whereby the efficiency of 20 the engagement of the boot jack with the foot portion of the boot will be greatly increased, thereby facilitating the removal of the boot.

With the foregoing objects in view, my invention contemplates the provision of certain improved details of the construction 25 and arrangement of the boot jack.

The nature and characteristic features of my invention will be more readily understood from the following description, taken 30 in connection with the accompanying drawings forming part hereof, in which:

Figure 1 is a perspective view showing a boot jack embodying the main features of my present invention in operative position, 35 the boots being shown with one of them in the process of removal;

Fig. 2 is a top or plan view of the boot jack, the same being shown with the toe engaging device in its extended position;

40 Fig. 3 is a similar view, but with the toe engaging device shown in its retracted position;

Fig. 4 is an underneath plan view of the parts in the same positions as shown in Fig. 45 3, but with the prop members shown in their retracted or collapsed position; and

Fig. 5 is a longitudinal section taken approximately on the line 5—5 of Fig. 3, but with the prop members shown in their operative position, and the toe engaging member partially extended.

Referring to the drawings, in the particular embodiment of my invention therein shown, 50 6 is the body portion of the boot jack, the same being preferably made of wood and having its forward end provided with a ta-

pered U-shaped recess 7. The recess 7 is provided for the purpose of engaging the heel portion of the boot in the customary manner.

60 The under side of the body portion 6 is provided with a pair of recesses 8, said recesses being located near the side margins of the body portion 6. Props 9 are pivotally mounted by means of pins 10 in the recesses 8. The props 9 are adapted to be seated within the recesses 8 as shown in Fig. 4, or swung outward so as to cause the body portion 6 to assume an inclined position, as shown in Figs. 1 and 5 of the drawings. A 65 cross bar 11 is secured at each end to the props 9, whereby said props may be swung outward from the recesses 8 in unison. The under side of the body portion 6 is provided with a button 12, over which the central portion 70 of the cross bar 11 is adapted to snap, thereby to limit the outward movement of the props 9 and to hold the same in the open position, thus insuring the correct positioning of said props.

75 For the purpose of engaging the toe portion of the boot, there is provided a cross bar 13 which is carried at the forward end of side bars 14. The side bars 14 are made of flat metal, preferably of a width corresponding to the thickness of the body portion 6, and extend along the sides thereof. The rear ends of the side bars 14 are connected by means of a cross strut 15, which extends across the top surface of the body portion 6. There are also provided ears 17, the same being continuations of the strut member 15, which ears 17 extend on the under surface of the body portion 6 and serve to confine the cross strut 15 to the top surface of the body portion 6, and thereby maintain the side bars 14 at all times in alinement with the body portion 6. The portions of the side bars 14 intermediate their ends extend through guide members 16, which are 80 secured to the forward end of the body portion 6, the arrangement being such that the bars 14 may slide through the guide members 16 when the toe engaging bar 13 is pulled out a sufficient distance, whereby the 85 toe portion of the boot may be properly engaged.

90 The operation of the device will, of course, be readily understood. The same being initially in the collapsed or folded condition, 110 the prop members 9 are first pulled outward so as to cause the body portion 6 to assume

the inclined position as shown in Figs. 1 and 5 of the drawings. The toe engaging member 13 is then pulled outward the proper distance, the amount of the extension of the same being dependent upon the size of the particular boots to be removed. As the toe engaging member is thus pulled outward, the side bars 14 will slide through the guides 16, and the cross strut 15 at the rear end of the side bars 14 will be carried to a position above the central portion of the body member 6, and when so positioned the same will be engaged by the other foot of the user as said foot is placed on the body portion 6 for the purpose of holding the boot jack while the boot on the other foot is being removed. In this manner, likelihood of accidental movement of the toe engaging bar will be reduced to a minimum.

It will, of course, be understood that after the props 9 and the toe engaging member 13 are properly positioned, the heel of the boot to be removed is positioned in the tapered U-shaped recesses 7 at the forward end of the body portion 6, and the toe of the boot is positioned under the toe engaging member 13. The other foot of the user being now placed upon the top surface of the body portion 6, the user may withdraw his leg and foot from the boot which is held by the boot jack as aforesaid.

It will be seen that there is thus provided a boot jack of novel construction and arrangement, which will be efficient in its action, and which may be readily folded for transportation or extended for use as desired.

Having thus described the nature and characteristic features of my invention, what I claim as new and desire to secure by Letters Patents, is:

1. A boot jack comprising a body portion provided with a heel engaging recess in the forward end thereof, said body portion having recesses in the under side and means adapted to be positioned within said recesses and to be extended therefrom to a fixed position to support the body portion in an inclined position.

2. A boot jack comprising a body portion provided with a heel engaging recess in the forward end thereof, said body portion having recesses in the under side, and props pivoted in said recesses and adapted to be folded therein or to be extended therefrom to a fixed position to support the body portion in an inclined position.

3. A boot jack comprising a body portion provided with a heel engaging recess in the forward end thereof, said body portion having recesses in the under side, props pivoted in said recesses and adapted to be folded therein or to be extended therefrom to a fixed position to support the body portion in an inclined position, a toe engaging mem-

ber, and means for adjustably supporting said toe engaging member.

4. A boot jack comprising a body portion provided with a heel engaging recess in the forward end thereof, said body portion having recesses in the under side, props pivoted in said recesses and adapted to be folded therein or to be extended therefrom to a fixed position to support the body portion in an inclined position, a toe engaging member, and side bars carrying said toe engaging member at their forward ends, said side bars being slidably positioned on the sides of the body portion.

5. A boot jack comprising a body portion provided with a heel engaging recess in the forward end thereof, said body portion having recesses in the under side, props pivoted in said recesses and adapted to be folded therein or to be extended therefrom to support the body portion in an inclined position, a toe engaging member, side bars carrying said toe engaging member at their forward ends, said side bars being slidably positioned on the sides of the body portion, and a cross strut connecting the rear ends of the side bars and positioned above the top surface of the body portion.

6. A boot jack comprising a body portion provided with a heel engaging recess in the forward end thereof, said body portion having recesses in the under side, props pivoted in said recesses and adapted to be folded therein or to be extended therefrom to support the body portion in an inclined position, a toe engaging member, side bars carrying said toe engaging member at their forward ends, said side bars being slidably positioned on the sides of the body portion, a cross strut connecting the rear ends of the side bars and positioned above the top surface of the body portion, and members for guiding the side bars intermediate their ends, said guide members being secured to the forward end of the body portion.

7. A boot jack comprising a body portion having sides extending parallel the entire length of the body portion and said body portion being provided with a heel engaging recess in the forward end thereof, a toe engaging member, and side bars carrying said toe engaging member at their forward ends, said side bars being slidably positioned on the sides of the body portion.

8. A boot jack comprising a body portion provided with a heel engaging recess in the forward end thereof, a toe engaging member, side bars carrying said toe engaging member at their forward ends, said side bars being slidably positioned on the sides of the body portion, and a cross strut connecting the rear ends of the side bars and positioned above the top surface of the body portion.

9. A boot jack comprising a body portion provided with a heel engaging recess in the

forward end thereof, a toe engaging member, side bars carrying said toe engaging member at their forward ends, said side bars being slidably positioned on the sides of the body portion, a cross strut connecting the rear ends of the side bars and positioned above the top surface of the body portion, and ears constituting continuations of said strut extending on the under side of the body portion.

10. A boot jack comprising a body portion provided with a heel engaging recess in the forward end thereof, a toe engaging

member, side bars carrying said toe engaging member at their forward ends, said side bars being slidably positioned on the sides of the body portion, a cross strut connecting the rear ends of the side bars and positioned above the top surface of the body portion, and members for guiding the side bars intermediate their ends, said guide members being secured to the forward end of the body portion.

In testimony whereof, I have hereunto signed my name.

WILLIAM G. MOLAND.
